COLLAR

Adolf Closmann, Leipzig, Germany, assignor to
Atlas Ago Chemische Fabrik, Aktien-Gesell-
schaft, Molkau, near Leipzig, Germany, a corpo-
ration of Germany

Application April 18, 1936, Serial No. 75,045
In Germany November 25, 1935

4 Claims. (Cl. 2—136)

The present invention relates to collars and, more particularly, to a collar of a reinforced character having greatly increased strength and improved wearing qualities.

Heretofore, collars of the conventional type generally had the tendency of tearing at certain points which have been particularly exposed to great stresses. Such danger points have been, for example, the two terminal portions of the folding edges and the button holes. When putting on the collar and adjusting the necktie these folding edges and the sides of the button holes have been exposed to considerable forces and have been easily torn due to the circumstance that the lower part of conventional collars could not yield in view of the closing or locking effect of the collar button while the upper portion of the collar yielded readily to the same forces. This difference in the displacement of the upper and the lower part caused great tension at the bending edges and at the edges of the button holes and frequently led to tearing of the material. Once the surface of the material constituting the collar was broken or torn to any limited extent, weak points exposed to perspiration and collecting dirt have been provided which rapidly destroyed the collar. This disadvantage was particularly troublesome in conventional paper collars which due to their inferior strength have been particularly exposed to quick destruction after a relatively short useful life. Although many suggestions and proposals have been made to eliminate this inconvenience and to solve this vexatious problem, none, as far as I am aware, of these various suggestions and proposals has been completely satisfactory and successful when carried into practice on a commercial and industrial scale.

I have discovered that the problem may be solved in a remarkably simple manner and that an improved collar may be provided which is substantially free from the disadvantages referred to hereinabove.

It is an object of the present invention to provide a collar of an improved and reinforced character which prevents breaking, tearing of the material of the collar at the points exposed to the greatest stresses and which has a useful life several times longer than that of conventional collars.

It is another object of the invention to provide an improved collar having reinforced folding edges and button holes so that tearing at these danger points is effectively prevented.

The invention also contemplates an improved collar of superior strength which may be readily manufactured from low-priced materials such as paper, cardboard and the like on a quantity production scale and by means of existing ma-
60 chinery.

Other and further objects and advantages of the invention will become apparent from the following description taken in conjunction with the accompanying drawing, in which:

Fig. 1 illustrates a front elevational view of a collar embodying the principles of the present invention showing the reinforcing portions in an unassembled condition.

Fig. 2 depicts a front elevational view of the collar shown in Fig. 1 after its assembly is finished and the product is ready for wearing.

Broadly stated, according to the principles of the invention, reinforcing portions are provided on the body of the collar particularly at the lateral cutting edges or corners and around the button holes. These reinforcing portions preferably double or treble the thickness and strength of the collar material at the exposed points and edges so that they are capable of resisting considerable forces of a shearing or tearing character. The extension pieces are, preferably, provided integrally with the body of the collar in the form of extension pieces at the lateral ends of the collar body and the collar tongues. In practical operation the body portion and the extension pieces of the collar may be cut or stamped out of a single sheet of a suitable material as, for example, a suitable composite paper sheet or board. Shallow grooves may be provided along the folding lines in order to facilitate folding back these extension pieces which are subsequently cemented to the corresponding surfaces of the body portion of the collar. It is essential that the extension portions to be folded back and cemented to the body portion or neck-band of the collar should exactly conform with the edges of the body portion and the button holes on the extension pieces have to exactly conform and register with the button holes proper on the neck band or body portion of the collar. A separate extension piece is, preferably, provided for the upper or folding portion of the collar and for the lower or neckband portion of the collar, the extension pieces of the upper and lower portions having such form as to slightly overlap. Thus, when first the extension of the neckband portion or tongue bearing the button hole is bent back and cemented and subsequently the extension of the upper or folding portion, the overlapping portion of the lower extension piece will be safely locked

preferred embodiment and the accompanying drawing.

Referring now more particularly to Fig. 1, a collar having a lower or neckband portion 1 and an upper or folding portion 2 is illustrated. Button holes 10 and 11 are provided at the two ends or tongues 7 and 8 of the neckband portion in the conventional manner. Integral extension pieces 3, 4 and 5, 6 are provided for the ends of the upper and lower portions, respectively, the extension pieces 5, 6 of the neck portion having such form as to accurately conform to the edges of tongue portions 7 and 8. Extension pieces 5 and 6 are provided with button holes 9 and 12 which exactly register with the button holes proper when the extension pieces are folded back along lines 15 and 16. The extension pieces 3 and 4 of the folding portion of the collar may be folded back along lines 13 and 14 and cemented to the body of the collar same as the extension pieces 5 and 6.

When the collar is first assembled the extension pieces 5 and 6 are folded back along lines 15 and 16 and cemented to the body of the collar, and subsequently extension pieces 3 and 4 along lines 13 and 14. Thus, the lower edge of extension pieces 3 and 4 will overlap and in part cover the tips 17 and 18 of extension pieces 5 and 6 whereby a reinforcing and locking effect will be provided. It will be noted that the material will have double thickness and double strength around the button holes and around the lateral edges of the folding portion and will have treble thickness and strength at 17 and 18 where the stresses and therefore the danger of tearing the collar is the greatest. This selective reinforcement of different portions of the collar in accordance with the stresses to be withstood is an exclusive feature of the present invention and is clearly illustrated in Fig. 2 of the drawing showing the collar embodying the principles of the invention in its finished form. In view of the simplicity of the structure and in view of the fact that identical reference numerals have been used to denote corresponding parts of Figs. 1 and 2, the finished product will be readily understood by those skilled in the art without further detailed explanation.

It is to be noted that the collar according to the invention is selectively reinforced at the points most exposed to the danger of tearing so that the principal disadvantage of conventional collars and particularly of paper collars has been successfully eliminated.

It is also to be observed that the reinforcement of the collar at the specified points has the additional advantage of increasing the stability of the collar and maintains the attractive appearance of the collar during wearing.

It is also noted that the collar according to the invention has no sharp and cut edges but all of the edges which are visible during wearing the collar have folded back and doubled edges whereby the impression of a real starched linen collar is closely simulated.

Although I have described my invention in connection with a preferred embodiment thereof, many variations and modifications may be resorted to by those skilled in the art without departing from the principles of the invention. I consider all of these variations and modifications as within the true spirit and scope of the invention as disclosed in the present specification and defined by the appended claims.

I claim:

1. A collar comprising a neckband portion, a folding portion, a lower extension piece on each end of said neckband portion, an extension piece on each end of said folding portion, and an upwardly extending tip on each lower extension piece, all of said extension pieces being folded back on fold lines extending transversely of the collar and bonded to register with the terminal regions of said neckband and folding portions to double the strength thereof, said upwardly extending tips being covered and locked by the extension pieces on said folding portion providing a reinforcement of triple strength for the upper front corners of said collar. 15

2. A collar integrally formed from a sheet of fibrous cellulosic material which comprises a neckband portion, a folding portion, a longitudinally extending integral lower extension piece on each end of said neckband portion, a longitudinally extending integral extension piece on each end of said folding portion, and an upwardly extending tip on each lower extension piece, all of said extension pieces being folded back on fold lines extending transversely of the collar and bonded to register with the terminal regions of said neckband and folding portions to double the strength thereof, said upwardly extending tips of said lower extension pieces being covered and locked by the lower edge of the extension pieces on said folding portion providing a reinforcement of triple strength for the upper front corners of said collar. 20 25

3. A collar integrally formed from a sheet of fibrous cellulosic material which comprises a neckband portion, a folding portion, a longitudinally extending integral lower extension piece on each end of said neckband portion, a longitudinally extending integral extension piece on each end of said folding portion, an upwardly extending tip on each lower extension piece, all of said extension pieces being folded back and bonded to register with the terminal regions of said neckband and folding portions to double the strength thereof, said upwardly extending tips of said lower extension pieces being covered and locked by the lower edge of the extension pieces on said folding portion providing reinforcement of triple strength for the upper front corners of said collar, and button holes located at the ends of said neckband portion and in said lower extension pieces registering with each other. 35 40 45 50

4. A collar integrally formed from a composite sheet of fibrous cellulosic material which comprises a neckband portion, a folding portion, a pair of lower extension pieces on said neckband portion integrally extending in longitudinal direction, a pair of extension pieces on said folding portion integrally extending the same in longitudinal direction, and an upwardly extending reinforcing tip on each lower extension piece, all of said extension pieces being folded back on fold lines extending transversely of the collar and cemented in registering position to the terminal regions of said neckband and said folding portions and overlapping each other to lock said tip of the lower extension pieces underneath the lower edge of the extension pieces on said folding portion providing double thickness and strength at the terminal regions of said collar and triple thickness and strength at the upper front corner thereof. 55 60 65 70
